UNITED STATES PATENT OFFICE.

CHARLES G. WEBER, OF EASTPORT, MARYLAND.

WEATHER-STRIP.

1,355,582.

Specification of Letters Patent. Patented Oct. 12, 1920.

Application filed March 17, 1919. Serial No. 283,072.

To all whom it may concern:

Be it known that I, CHARLES G. WEBER, a citizen of the United States, residing at Eastport, in the county of Anne Arundel, 5 State of Maryland, have invented certain new and useful Improvements in Weather-Strips; and I do hereby declare the following to be a full, clear, and exact description of the invention, such as will enable others 10 skilled in the art to which it appertains to make and use the same.

This invention relates to new and useful improvements in weatherstrips and particularly to weatherstrips used on the bottoms of doors.

The principal object of the present invention is to provide a novel and improved weatherstrip which will automatically close the opening between the bottom of the door 20 and the floor or sill to exclude air, rain, and snow.

Another object of the present invention is to provide a novel and improved device of this character which is capable of being applied to any door, either a sliding door or a hinged door, and which will move into operative position when the door is in closed position, and into inoperative position when the door is in open position.

30 Other objects and advantages will be apparent from the following description when taken in connection with the accompanying drawing.

In the drawing:

35 Figure 1 is an elevation of the lower portion of a door having my improved weatherstrip applied thereto.

Fig. 2 is a vertical sectional view taken on the line 2—2 of Fig. 1.

40 Fig. 3 is an elevation of this weatherstrip from the inside.

Fig. 4 is a vertical sectional view taken on the line 4—4 of Fig. 1.

Fig. 5 is an elevation like Fig. 3, but with 45 the movable member of the weatherstrip in elevated position.

Referring particularly to the accompanying drawings, 10 represents the bottom portion of a door, and 11 the side of the door frame to which the door is hinged, while 12 represents the sill of the door frame. Secured to the lower portion of the outer face of the door, and extending the full width of the door, is a housing such as a strip of 50 wood, metal, or other desired material 13. Formed longitudinally in the upper portion

of the inner face of the strip 13 is a groove 14 in which is disposed a rod 15, one end of which is arranged to engage with the adjacent face of the portion of the door casing 60 or frame on which the door is hinged. The other end of this rod is threaded and has a block 16 threaded thereon, said block of a size to fit into the groove for longitudinal movement without turning in the groove. 65 To the inner face of the block, that is, next the face of the door, there is pivoted one arm 17 of a bell crank lever. Below the grooved portion of the strip, there is formed a longitudinal recess 18, and disposed in 70 this recess for vertical slideable movement, is the body 19 of the weatherstrip. Secured to one face of this body 19 is a strip of felt 20, the felt and body being formed with upright slots 21 for the passage of the 75 screws 22 by means of which the strip 13 is secured to the door, and which permit the strip 19 to slide. Secured to the upper wall of the recess 18 is a hook-shaped-keeper 22', in which the before-mentioned lever is ful- 80 crumed, its lower arm 23 normally resting within a depression 24 formed in the upper edge of the body member 19. Formed vertically through the upper wall of the recess are openings 25 in which are seated the up- 85 per ends of the coil springs 26. The lower portions of these springs are seated in open- 90 ings 27 formed in the body 19 and normally urge this weather strip upwardly so that the lower edge thereof is flush or level with the 95 lower edge of the door. Additional screws 28 are passed through the strip 13 between the groove and the recess and into the face of the door.

When the door is in open position the 95 springs 26 hold the body 19 in elevated position and project the outer end of the rod 15 beyond the inner end of the strip 13. When the door is moved into closed position the projecting end of the rod is pushed in- 100 wardly with the result that the block 16 will cause the rocking of the bell crank lever and the downward movement of the body 19 by the pressing engagement of the arm 23 upon the upper edge of said body. This 105 forces the lower edge of the felt against the carpet strip or threshold 29 of the door-frame, and excludes wind, rain and snow. The device is constructed for attachment to any door without modifications to the door, 110 and may be made of metal if desired without departing from the invention.

All parts of this device are accessible from the inner side of the housing 13 before it is applied to the door. After it is applied thereto the door may be swung open and the 5 rod 15 grasped by its projecting end and turned to adjust it through the nut or block 16 one way or the other, as the user finds it necessary to cause the weather-strip to be borne downward to the threshold with exactly 10 the proper pressure. From time to time as the parts shrink or conditions change otherwise, it may be found desirable to further adjust the rod, although the entire mechanism is immediately accessible when 15 the fastening screws are removed and the casing taken off the door.

What is claimed is:

The herein described weather-strip comprising a casing having a longitudinal groove and below it a channel, a strip 20

mounted for vertical movement in said channel and carrying packing, means holding this strip normally raised, a block mounted to slide in said groove and having a threaded opening, a bell-crank lever pivoted in the casing and having one end pivoted to the block and the other end bearing on said strip, and a rod mounted in said groove and threaded at one end for engagement with the opening in the block, its other end normally projecting at one end of the casing adjacent that edge of the door which is hinged, as described. 25 30

In testimony whereof, I affix my signature, in the presence of two witnesses.

CHARLES G. WEBER.
